(57) **CLAIM**

The ornamental design for “a lamp”, as shown and described.

DESCRIPTION

FIG. 1 is a front view of “a lamp” showing my design;

FIG. 2 is a rear side view thereof;

FIG. 3 is a left side view thereof;

FIG. 4 is a right side view thereof;

FIG. 5 is a top plan view thereof; and,

FIG. 6 is a bottom plan view thereof.

In the above Figures, the portion that is shown in broken lines is for illustrative purpose only and forms no part of the claimed design.
